Contt. B. Mueller.

UNITED STATES PATENT OFFICE.

JAMES E. DOYLE, OF CLEVELAND, OHIO.

SUCTION-NOZZLE HEATER FOR PRINTING-PRESSES.

1,196,440.

Specification of Letters Patent. Patented Aug. 29, 1916.

Application filed May 6, 1915. Serial No. 26,369.

To all whom it may concern:

Be it known that I, JAMES E. DOYLE, a citizen of the United States, residing at Cleveland, in the county of Cuyahoga and State of Ohio, have invented a new and useful Improvement in Suction-Nozzle Heaters for Printing-Presses, of which the following is a specification, the principle of the invention being herein explained and the best mode in which I have contemplated applying that principle, so as to distinguish it from other inventions.

My invention has more particular reference to the application of a heating element to some feasible type of suction device and specifically adjacent the mouth or intake opening thereof.

It is common in the printing art to pass a freshly printed sheet through a heated zone in order to prevent offset. So far as I am aware, however, this preventive agency has never been combined with a suction device purposed to remove loose particles from the sheet preparatory to printing thereon, with a coaction in the way of effective accomplishment of one of the results sought.

Consonantly my object has been to make possible the coöperation of a suction effect such that the moving sheet is compelled to travel not only through a heated zone but in definitely prescribed proximity to the source of heat.

My invention not only dries the sheet but neutralizes or abstracts its static electricity.

I would have it expressly understood that I in no wise limit myself to this specific application or embodiment of my invention, which I have selected as a basis for illustrating and describing my invention merely for the purpose of rendering a clear and comprehensive understanding of the scope and novel features thereof.

Adverting to the drawings: Figure I is a diagrammatic plan view showing the application of my invention to the cylinder of a printing press. Fig. II is an enlarged section on line AA of Fig. I. Fig. III is a similarly enlarged end view looking into the mouth of the nozzle as suggested by line BB on Fig. II. Fig. IV is a still further enlarged section of the heating element.

The cylinder of the printing press in association with which I have elected to illustrate my invention is designated with the reference numeral 1.

At some suitable location is a suction

motor 2 which is operatively connected with a flexible header duct 3 and this in turn with a manifold 4 having a plurality (eight) of branches 5. The branches 5 are coupled at 6 with a corresponding number of constricted outlets of a nozzle structure 7 which may be either of integral manufacture or comprise a similar number of flared nozzles suitably secured together. The drawings show a plurality of distinct nozzles fastened together in a manner presently to be explained. The arrangement of the flared nozzles 7 is preferably though not necessarily such that their narrow and elongated intake openings 8 are closely alined across and adjacent to the periphery of the cylinder 1. The nozzles 7 are supported by an angle 8^a which is carried by the press and which may be either stationary, movable relative to or movable in unison with the sheet conveyer.

The several nozzles 7 are each fashioned above and below with flanges 9 against which corresponding flanges 10 upon a heating element 11 are to be removably and adjustably attached by means of slots 9^a and screws 9^b as clearly appears in Fig. III. The adjustability is primarily to allow for expansion and contraction of the heating element. In the form shown there are two heating elements 11 extending the entire length of the combined intake openings 8 and located just above and below the same as is seen in both Figs. II and III. Mention is made that the two elements when thus supported form a continuous inlet slot which should be presumed as in most efficient proximity to the periphery of the cylinder. Such arrangement accordingly effects the advantages otherwise attained and claimed in my copending application entitled "Suction nozzle for printing presses" filed of even date herewith and bearing Serial No. 26,368. The heating elements 11 quite arbitrarily are made to functionate through the agency of electricity supplied to an interior coil 12 disposed in packing 13 and insulated by air chambers 14 in all directions with the exception of one which is opposed to the periphery of the cylinder 1. In such direction the heating element presents a mica sheet 15 and protecting cover 16 whereby the heat is radiated almost exclusively therethrough, and thus intensified and made more effective for the purposes of my present invention. The

cover 16 is additionally fashioned with diagonal grooves 17 which are clearly seen in Fig. III. The purpose of such grooves is to make possible the employment of a very strong suction effect without warping or otherwise disarranging the sheet during its travel past the intake of the nozzle.

My invention obviates the necessity of drying the ink on a printed sheet elsewhere with some special heat supplying agency. It also neutralizes or sufficiently abstracts the electricity which manifests itself in all paper stock thereby presenting the same in better condition to the type form.

15 I claim:

1. An appliance of the character described, comprising in combination with a sheet conveyer, a suction nozzle opposed thereto, means for establishing a suction effect through said nozzle, and a heating surface contiguous to the edge of the nozzle opening.

2. An appliance of the character described, comprising in combination a sheet conveyer, a suction nozzle opposed thereto, means for establishing a suction effect through said nozzle, and a heating element adjustably carried by the mouth of said nozzle whereby to compensate for expansion and contraction of said element.

3. An appliance of the character described, comprising in combination with a sheet conveyer, a suction device having a long narrow intake opening opposed across said conveyer, means for creating a suction draft through said opening, and a heating member interposed between said device and conveyer and spaced from the latter, said member having the major portion of its exterior surface insulated to leave a long narrow radiating surface, the latter being opposed to said conveyer.

4. An appliance of the character described, comprising in combination with a sheet conveyer, a suction nozzle having a long narrow intake opening opposed to said conveyer, means for creating a suction in said nozzle, and a pair of heating elements carried by said nozzle and extending along opposite sides of said intake opening.

5. An appliance of the character described, comprising in combination with a sheet conveyer, a plurality of suction nozzles having mouths opposed thereto, a manifold connecting the outlets of said nozzles, suction means in communication with said manifold, and a heating member extending along all of said nozzle mouths and between the same and said conveyer.

6. A suction nozzle comprising a hollow member and a heating element carried thereby adjacent the intake opening thereof.

7. A suction nozzle comprising a hollow member having a long narrow intake opening adapted to be opposed to a given surface with a relative movement between said member and surface, and a heating element secured to and extending along one side of said opening whereby not to obstruct the latter.

8. A suction appliance comprising a plurality of nozzles having alined openings, a manifold connected with said nozzles, and a heater connecting and extending adjacent said openings.

9. An appliance of the character described, comprising the combination of a sheet conveyer on which a sheet is adapted to travel, a suction nozzle having its mouth opposed to said conveyer, means for establishing a suction effect in said nozzle, and a heater mounted adjacent said nozzle intake and having that surface which is opposed to said conveyer fashioned with diagonal grooves.

10. An appliance of the character described, comprising the combination of a sheet conveyer, a suction nozzle having an intake opening opposed thereto, means for establishing a suction effect through said nozzle, and a heating device mounted adjacent said nozzle and along said opening.

11. An appliance of the character described, comprising the combination of a sheet conveyer, a suction nozzle opposed thereto, and means for establishing a heated zone about the mouth of said nozzle.

12. An appliance of the character described, comprising a sheet conveyer, suction nozzles having alined intake openings opposed thereto, means for establishing a uniform suction through said nozzles, a structure forming a continuous slot across said nozzle openings, and means for heating said structure adjacent such slot.

13. An appliance of the character described, comprising a sheet conveyer, suction nozzles having alined intake openings opposed thereto, means for establishing a uniform suction through said nozzles, and a heating member for joining said nozzle openings into a common continuous intake slot extending across the width of the passing sheet whereby to insure a uniform application of the suction effect.

Signed by me, this 30th day of April, 1915.

JAMES E. DOYLE.
